(57) **CLAIM**

The ornamental design for a hinge and pin assembly for container, as shown and described.

DESCRIPTION

FIG. 1 is an upper perspective view of a hinge and pin assembly for container showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrating a container depict environmental subject matter that form no part of the claimed design.

1 Claim, 4 Drawing Sheets
